US00D991283S

(12) **United States Design Patent** (10) Patent No.: **US D991,283 S**
Bachman et al. (45) Date of Patent: ** Jul. 4, 2023

(54) **DISPLAY SCREEN OR PORTION THEREOF WITH GRAPHICAL USER INTERFACE**

G06F 3/0486; G06F 3/0488; G06F 3/04886; G06F 9/4443; G06F 17/211; G06F 17/212

See application file for complete search history.

(71) Applicant: **Apple Inc.**, Cupertino, CA (US)

(72) Inventors: **William Martin Bachman**, San Jose, CA (US); **Jai Chulani**, Los Altos, CA (US); **Lynne Allison Sandberg Kress**, Santa Clara, CA (US); **Jeff Ma**, Emerald Hills, CA (US); **Parry Panesar**, Mountain View, CA (US); **Jeffrey L. Robbin**, Los Altos, CA (US); **Jim Young**, Livermore, CA (US)

(73) Assignee: **Apple Inc.**, Cupertino, CA (US)

(**) Term: **15 Years**

(21) Appl. No.: **29/849,377**

(22) Filed: **Aug. 10, 2022**

Related U.S. Application Data

(63) Continuation of application No. 29/778,031, filed on Apr. 9, 2021, now Pat. No. Des. 962,275, which is a continuation of application No. 29/689,370, filed on Apr. 29, 2019, now Pat. No. Des. 916,109, which is a continuation of application No. 29/615,316, filed on Aug. 28, 2017, now Pat. No. Des. 847,177, which is a continuation of application No. 29/548,004, filed on Dec. 9, 2015, now Pat. No. Des. 795,899, which is a continuation of application No. 29/507,923, filed on Oct. 31, 2014, now Pat. No. Des. 747,336, which is a continuation of application No. 29/415,033, filed on Mar. 6, 2012, now Pat. No. Des. 716,825.

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The peripheral broken lines in the FIGURE show a display screen or portion thereof and form no part of the claimed design. The broken lines within the FIGURE show portions of graphical user interface for a display screen or portion thereof which form no part of the claimed design.

1 Claim, 1 Drawing Sheet
